UNITED STATES PATENT OFFICE

WILLIAM C. REED, OF CHICAGO, ILLINOIS.

CAR-AXLE BOX AND LID.

1,095,737.

Specification of Letters Patent.

Patented May 5, 1914.

Application filed June 28, 1909. Serial No. 504,722.

To all whom it may concern:

Be it known that I, WILLIAM C. REED, a citizen of the United States, residing at Chicago, in the county of Cook and State of Illinois, have invented certain new and useful Improvements in Car-Axle Boxes and Lids; and I do hereby declare the following to be a full, clear, and exact description of the invention, such as will enable others skilled in the art to which it appertains to make and use the same.

This invention relates to car axle box lids, and has for its object to improve the same in the several particulars hereinafter noted.

15 The invention consists of the novel devices and combinations of devices hereinafter described and defined in the claims.

In some respects this invention is in the nature of an improvement on the car axle 20 box lid disclosed and claimed in Letters Patent of the United States, reissue to A. C. McCord, of date February 7, 1899, under Reissue No. 11,716, and in other respects it is in the nature of an improvement on the devices disclosed and claimed in Letters Patent 25 No. 803,155, granted to W. G. Dunham, of date October 31, 1905, entitled "Car axle box lids." In the said prior McCord patent, the lid is connected to a hinge lug on the box, 30 by trunnions arranged to engage elongated seats in said lug, and these seats are provided with entrance channels extending to the rear of the lug. The said rearwardly 35 opening entrance channels were found to be objectionable in that they allow the admission of dirt into the top of the box. In this improved lid construction, the lid is provided with a journal for co-operation with a seat in the hinge lug of the box, and this

40 journal seat is provided with an upwardly extended entrance channel that is preferably always covered by a hood or upper end portion of the lid, so that no dirt can enter the box therethrough. Preferably the lid 45 journal is afforded by axially alined, but laterally spaced trunnions cast integral with the lid, and the seats and entrance channels therefor, are formed in the sides of the hinge lug, so that said journal is a divided 50 or duplicate structure.

By flattening the journal or trunnions or making the same segmental instead of cylindrical in cross section, it is possible to make the entrance channel or channels therefor narrower than the greatest diameter of the said trunnion or journals, and thus to

positively prevent the lid from becoming unseated, except when turned or forced to one position, and which position the said journal or trunnion will never assume when 60 the lid is being operated.

In the accompanying drawings which illustrate the invention, like characters indicate like parts throughout the several views.

Referring to the drawings: Figure 1 is a view chiefly in front elevation, but with some parts broken away, and with some parts sectioned on the line x^1-x^1 of Fig. 3; Fig. 2 is a fragmentary view in front elevation, showing a portion of the box and 70 a portion of the plunger stem of the lid closing device, the lid being removed; Fig. 3 is a vertical section taken on the line x^3-x^3 of Fig. 1, showing the lid closed, some parts being broken away; Fig. 4 is a view corresponding to Fig. 3, but showing the lid 75 opened up; and Figs. 5 and 6 are fragmentary views in section, respectively, transversely and longitudinally of the box, illustrating a slightly modified construction. 80

The numeral 1 indicates an axle box of standard construction, but which at its upper portion adjacent to its mouth opening 2, is formed with a heavy hinge lug 3 having vertically elongated trunnion seats 85 4 in its sides. The trunnion seats 4 are provided with upwardly extended trunnion entrance channels 5, and just to the rear thereof, it is formed with an upwardly extended lock shoulder 6. The lug 3, on its 90 outer surface, is provided with laterally spaced flanges 7 formed on their faces with relatively small trunnion seats 8, having contracted forwardly extended entrance passages 8^a. 95

The lid 9 which is preferably a malleable iron or steel casting, is formed at its upper portion with a central pocket 10 that bulges outward and embraces the hinge lug 3 of the box. On its sides, the pocket 10 is 100 formed with axially alined inwardly projecting trunnions 11 shown as cast integral therewith. These trunnions 11 are flattened or made segmental, and are of such dimensions that they can be passed through the 105 entrance channels 5 of the hinge lug 3, only when the flattened sides of said trunnions are turned into alinement with the said channels. When the lid is closed, the upper rear edge 12 of the hood 10 engages the 110 shoulder 6 of the lug 3, and a lock flange 13 on the said lid engages with a rib 14

formed at the lower edge portion of the box opening 2, and thus the lid is held in its locked position in such manner that it can be moved into its open position only by a 5 combined sliding and pivotal movement. The lid 8, on its inner face, has an integrally cast or otherwise rigidly secured perforated bearing lug or bracket 15, through which the stem of a T bolt 16 works freely. The 10 head of the T bolt 16 is formed at its ends with flattened trunnions 17, that are adapted to be moved into the trunnion seats 8 of the lug 3, and to be interlocked therewith by rotation. A spring 18 surrounds the stem 15 of the T bolt 16, and is compressed between the perforated portion of the lid lug 15 and a collar 19 on the said T bolt.

By reference to Fig. 3, it will be noted, that when the lid is closed, the spring 18 20 exerts a force which tends to hold the said lid closed, and to press the same downward and against the face of the box; and that when the lid is turned into its open position, shown in Fig. 4, the said spring is then 25 thrown to the other side of its dead center, and then exerts a force which yieldingly holds said lid in its open position. When the lid is in its open position, its trunnions 11 are moved into the upper extremities of 30 the trunnion seats 4, but said trunnions are then turned into a position in which their greatest diameter is transverse of the entrance channels 5, and hence, cannot be removed through the said channels. When the 35 lid is in its closed position, the spring 18 holds the trunnions 11 in the lower portions of the said trunnion seats 4, so that it is not possible at any time for the lid to become accidentally detached from the box, 40 but it will be noted by reference particularly to Fig. 3, that when the lid is in a closed position, it is supported from the box, against the tension of the spring 18, in such a manner that the flattened journal 11 45 will be held slightly above the bottom of the seat 4. In practice, the lid when thus seated, may be supported by engagement of the lid flange 13 with the box rib 14, or by engagement of the upper edge 12 of the 50 lid hood with the hinge lug; or this engagement made between the lid and box may be simultaneously at both points, or, for that matter, at some other point. The 55 gist of this arrangement is that when the lid is closed, it is seated on the box in such manner that wear will not then be upon the lid journal. When the lids are malleable castings with integral journals, this arrangement for preventing wear on the lid 60 journal when the lid is closed is especially important. To detach the lid from the box, it is necessary to slide the lid upward on the face of the box against the tension of the spring 18, far enough to force the trunnions 11 upward and outward through the

entrance channels 5, and this, as is evident, requires very considerable force. When the lid is in its open position, the rear edge 12 of the lid hood 10 rides on the rounded back portion of the hinge lug 3, but as preferably constructed at all times, the said hood covers the entrance channels 5, so that no dirt can enter the box therethrough. 70

In the construction illustrated in Figs. 5 and 6, the hinge lug 3 is provided with a journal seat 4^a having an entrance channel 5^a, that extends entirely through the said lug; and the lid 9 is provided with a flattened journal or shaft 11^a, which latter is shown as cast integral with the said lid, 80 but which might be a separately formed part suitably connected thereto. The operation of this modified arrangement is the same as that of the above described construction, wherein the journal on the lid is 85 formed by the flattened trunnions 11.

What I claim is:

1. The combination with an axle box and a lid hinged thereto, one of said members having a journal seat with an entrance channel leading thereto, and the other member having a journal insertible into said seat through said entrance channel, the said journal and seat connecting said lid to said box with freedom for pivotal and sliding 95 movements of the lid in respect to the box, a spring reacting against said lid and box, movable from one side to the other of a dead center, and when the lid is closed, exerting a downward force thereon, tending to move the journal thereof downward in said seat and away from said entrance channel.

2. The combination with an axle box and a lid hinged thereto, said box having a hinged lug provided with a seat formed with a contracted entrance channel, of a lid provided with a flattened journal insertible into said seat through said contracted entrance channel, when the lid is in a predetermined position, the said lid having a sliding, as well as a pivotal movement, and a spring re-acting against said lid and box, movable from one side to another of a dead center, and when the lid is closed, exerting a downward force thereon, tending to move the flattened journal thereof downward in said seat and away from said contracted entrance channel. 110

3. The combination with an axle box and a lid hinged thereto, said box having a hinge lug provided with a seat formed with a contracted upwardly extended entrance channel, of a lid provided with a flattened journal insertible into said seat through said contracted entrance channel; when the lid is in a predetermined position, the said lid having a sliding as well as a pivotal movement, and a spring reacting against said lid and box, movable from one side to the other of the 120

125

130

other of a dead center, and when the lid is closed, exerting a downward force thereon, tending to move the flattened journal thereof downward in said seat and away from said contracted entrance channel, said lid having a hood that covers said entrance channel in all positions of said lid.

4. The combination with an axle box having a hinge lug formed with a seat and with 10 a contracted upwardly extended entrance channel thereto, of a lid provided with a flattened journal insertible into said seat through said contracted entrance channel, when said lid is turned into a predetermined 15 position, said lid having a hood portion engageable with said hinge lug and arranged

always to cover said entrance channel, the said lid being free for pivotal and sliding movements and having a part arranged to interlock with the box by sliding movement, 20 and a compression spring reacting against said lid and box, movable from one side to the other of a dead center and tending to hold said lid in its closed or open position, depending on the position in which the lid 25 is set.

In testimony whereof I affix my signature in presence of two witnesses.

WILLIAM C. REED.
